UNITED STATES PATENT OFFICE

2,451,302

PIPE-BENDING MACHINE

Alva E. Peters, Olney, Ill.

Application March 14, 1946, Serial No. 654,265

2 Claims. (Cl. 153—38)

1

This invention relates to machines for bending pipes and while it is especially suited for use in bending short lengths of pipe, it obviously could be employed for bending pipes of any lengths.

One of the objects of the invention is to provide a machine having relatively movable supporting dies constituting rests or seats for the pipe to be bent, an intermediate or pressing die being positioned for exerting pressure against the supported pipe at a point between the rests, this die having its working face shaped to give the proper curvature to the bend of the pipe.

Another object is to provide a machine of this character, the pressing die of which can be actuated by a hydraulic ram or the like.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a vertical transverse section through the machine, parts being broken away.

Figure 2 is a section on line 2—2 Fig. 1.

Figure 3 is a section on line 3—3 Fig. 1.

Referring to the figures by characters of reference 1 designates standards which can be formed of channelled members extended upwardly from and welded or otherwise joined to base strips 2. Lower side beams 3 are joined to the sides of the standards 1 by bolts 4 insertable into selected openings 5 in the sides of the channelled standards. These openings are arranged in vertical series so that it thus is possible to adjust the lower side beams upwardly or downwardly relative to the standards.

Cross bars 6 are mounted on the beams 3 and are joined to the die supporting members 7 of a bed frame. These members 7 are provided with longitudinal series of openings 8 and selected openings are adapted to receive stop pins 9 extending upwardly from the members 7.

Bottom forming dies 10 are extended transversely of the gap between the members 7 and are provided with cross pins 11 overlying the members 7 and adapted to abut against the adjacent stop pins 9. Thus the forming dies 10, a pair of which are provided, can be held against

2

movement away from each other after they have been placed in a predetermined relative position and can adjust themselves to the engaged work. It is to be understood, of course, that the upper surface of each of these forming dies is to be recessed, as shown at 12, thereby to form a seat for a pipe P to be bent.

The upper portions of the standards 1 are joined at their sides by top side beams 13, on 10 which is mounted a cross head 14 provided with a depending socket member or guide 15. A jack indicated generally at 16 is adjustably connected to the cross head by means of a screw threaded stem 17. This stem is rotatably engaged by 15 a nut 18 swiveled on a post 19 extending from the cross head and rotatable by means of a hand wheel 20 or the like. Thus by rotating this hand wheel the jack 16 can be quickly raised or lowered relative to the cross head and within the 20 guide 15.

Jack 16 has a plunger 21 which extends downwardly therefrom and to the lower end of which is detachably joined an upper forming die 22. This plunger is adapted to be directed downwardly by hydraulic pressure or other suitable means, a controlling lever for the hydraulic mechanism being indicated at 23. This hydraulic mechanism constitutes no part of the present invention because any suitable type can be utilized. It is merely necessary to utilize a hydraulically operated forming die which can be quickly adjusted bodily to raise or lower the same relative to the bed frame.

The top forming die 22 has a recess 24 providing a seat for the pipe to be bent and this recess is preferably curved in the direction of its length, as indicated in Figure 1, so as to determine the curvature of the pipe at the bend following the bending operation. Obviously the curvature of the pipe at the bend can be varied by changing the forming die 22; substituting a die having a forming surface of one configuration for another die having a forming surface of a different configuration.

In practice the forming dies 10 are positioned 35 at a distance apart to properly support the pipe beyond the point where the bend is to be made, these forming dies 10 being held against spreading movement relative to each other by the co- 40 operating pins 9 and 11. After the proper adjustment has been effected and a die 22 of proper configuration has been placed in position, the pipe P is placed on the forming dies 10. Thereafter the jack 16 is quickly adjusted downwardly 45 to bring the forming die 22 into contact there-

with so that the pipe will rest in the seat 24 at the lowest portion thereof. The next step is to apply hydraulic pressure to the forming die 22 which thus is forced downwardly so as to bend the pipe, the configuration of the pipe at the bend conforming with the configuration longitudinally of the seat 24.

It is to be understood, of course, that the pipe generally should be filled with some material to resist crushing during the bending operation. This is a well known practice.

It has been found that after making proper adjustments of the parts the mass production of pipes of uniform configuration is greatly speeded.

What is claimed is:

1. In a pipe bending machine, a frame, the frame including upstanding standards, spaced parallel die supporting members carried thereby, and means for effecting vertical adjustment of the die supporting members relative to the standards, bottom forming dies, cross-pins carried by said dies and resting upon the die supporting members, said cross-pins being non-connected to the die supporting members, whereby to permit free pivoting of the dies upon said members and free sliding movement of each die relative to said members, stop means adjustable longitudinally of the die supporting members and adapted to engage the outer ends of the dies, whereby to limit movement of the dies away from each other, said dies having pipe receiving seats for supporting a pipe bridging the space between the dies, an upper forming die positioned over the space between the bottom forming dies and having a pipe receiving seat in its lower surface, and means for forcing the top forming die against the supported pipe to bend

the pipe to the longitudinal configuration of the seat in said top forming die.

2. In a pipe bending machine, a frame including standards and connections between the standards, means for adjustably raising and lowering said connections relative to the standards, a bed frame mounted on said connections and including die supporting members each having a longitudinal series of apertures, stop pins insertable in any of the apertures, bottom forming dies, cross-pins projecting from the sides of the dies and non-connectedly supported for sliding and pivotal movement upon the die supporting members, said stop pins being engageable by the cross-pins, whereby to limit slidable movement of the dies away from each other, said forming dies having pipe receiving seats, there being a gap between the dies, a cross head mounted on the frame, a jack adjustably connected to and suspended therefrom, and a top forming die detachably connected to the jack and positioned above the gap, said top forming die having a seat in its lower face for the reception of that portion of the pipe to be bent, said seat being curved in the direction of its length.
